US00D797867S

(12) **United States Design Patent** (10) **Patent No.:** **US D797,867 S**
(45) **Date of Patent:** **** Sep. 19, 2017**

(54) **EXERCISE BAG**

(71) Applicant: **Mark Thorpe-Apps**, Nanning (CN)

(72) Inventor: **Mark Thorpe-Apps**, Nanning (CN)

(**) Term: **15 Years**

(21) Appl. No.: **29/529,864**

(22) Filed: **Jun. 11, 2015**

(51) **LOC (10) Cl.** **21-02**

(52) **U.S. Cl.**

USPC **D21/680**

(58) **Field of Classification Search**

USPC ... 482/106, 51, 93, 109, 110, 139, 142, 148, 482/44, 45, 46, 141, 95, 50, 129, 127, 482/140, 23, 907; D21/680, 798, 692, D21/662, 804, 686, 671, 691, 682, 694, D21/687, 654, 487, 679, 684, 688, 412, D21/685, 400, 791, 725, 386, 627; D24/188, 211, 141, 215, 190, 200, 231, D24/106, 171; D30/160, 119, 152; D6/601, 598, 604, 691.4, 597, 348, 361, D6/596, 606; 601/112, 121, 122, 46, 15, 601/19, 120, 134, 135, 131; 220/4.07, 220/4.24, 4.27, 666; D3/307, 290, 299, D3/289, 287, 254, 246; 476/256, 519, 476/549, 558, 559, 564, 118, 457, 219, 476/513, 560, 568, 409

CPC A63B 21/4035; A63B 21/0552; A63B 23/0211; A63B 23/12; A63B 2210/50; A63B 21/0557; A63B 21/0004; Y10S 482/907; A61H 15/0092; A61H 15/00; A61H 2201/1284; A61H 1/0244; A61H 1/0292

(57) **CLAIM**

The ornamental design for an exercise bag, as shown and described.

DESCRIPTION

FIG. 1 shows a perspective view of my claimed design.

FIG. 2 shows a top view of my claimed design.

FIG. 3 shows a bottom view of my claimed design.

FIG. 4 shows a front view of my claimed design.

FIG. 5 shows a rear view of my claimed design.

FIG. 6 shows a view from one side of my claimed design.

FIG. 7 shows a view from the other side of my claimed design; and,

FIG. 8 shows a further perspective view of my claimed design with two straps.

1 Claim, 4 Drawing Sheets
